UNITED STATES PATENT OFFICE.

PRESSLEY P. MARSH, OF SOUTH GREENFIELD, MISSOURI.

WELL-DRILLING MACHINE.

SPECIFICATION forming part of Letters Patent No. 592,155, dated October 19, 1897.

Application filed December 23, 1896. Serial No. 616,756. (No model.)

To all whom it may concern:

Be it known that I, PRESSLEY P. MARSH, a citizen of the United States, residing at South Greenfield, in the county of Dade and State 5 of Missouri, have invented a new and useful Well-Drilling Machine, of which the following is a specification.

My invention relates to well-drilling apparatus, and has for its object to provide means 10 for communicating an oscillatory or twisting movement alternately in opposite directions to the drill-rope, to impart a corresponding movement to the tools, whereby irregularities in the densities of strata through which the 15 tools pass may be prevented from deflecting the spudding-tools and enabling a straight hole to be drilled; to provide means for automatically reversing the direction of rotation or oscillation of the devices whereby motion 20 is communicated to the drill-rope, and, furthermore, to provide improved means for controlling the feed of the drill-rope.

Further objects and advantages of this invention will appear in the following description, 25 and the novel features thereof will be particularly pointed out in the appended claims.

In the drawings, Figure 1 is a perspective view of a drilling apparatus constructed in accordance with my invention. Fig. 2 is a 30 plan view, partly in section, through the slide-box. Fig. 3 is a transverse vertical section to show the means for shifting the slide. Fig. 4 is a detail view of the means for preventing the unreeling of the drill-rope from the drum or bull-wheel. Fig. 5 is a detail view in perspective of the mechanism for automatically feeding or "paying out" the drill-rope. Fig. 6 is a detail vertical section of the oscillatory 35 rope-guide. Fig. 7 is a detail view of the rope-guide, detached. Fig. 8 is a similar view of one of the rope-guide journal-boxes. Fig. 9 is a view of the rope-slide, detached. Fig. 10 is a detail transverse section of the same. Fig. 11 is a detail view of the means for communicating motion from the drive-shaft to the 40 counter-shaft. Fig. 12 is a detail view of the means for communicating motion to the trip. Fig. 13 is a detail view of the means for adjusting the throw of the feed-pawl.

Similar numerals of reference indicate cor-

responding parts in all the figures of the drawings.

Arranged at one end of the supporting-frame 1 is a derrick-post 2, provided at its 55 upper end with a guide-pulley 3 for the drill-rope 4, which supports the tools 5. The other end of the drill-rope is attached to and reeled upon a drum or bull-wheel 6, and passes at an intermediate point around a spudding-pulley 60 7, carried by a spudding-lever 8.

The drum carries a gear 9, with which meshes a pinion 10 on a feed-shaft 11, a ratchet 12 being arranged contiguous to and preferably rigid with said pinion, and being adapted 65 to be engaged, to prevent the feeding or paying out of the drill-rope, by means of a pawl 13. Any suitable means may be provided for holding this pawl out of engagement with the ratchet-wheel—such as a supporting-button 70 14, adapted to be arranged at its extremity in the path of the pawl.

The feed-shaft 11 carries a worm-gear 15, arranged in engagement with a worm 16, the worm-spindle 17 carrying a feed-ratchet 18, 75 which meshes a feed-pawl 19, and this feed-pawl is carried by a swinging arm 20, connected terminally to a pitman 21, which extends downwardly to the rocker-shaft 22, 80 forming a part of the spudding-lever. In order to vary the throw of the feed-pawl, and thus vary the amount of movement of the drum in paying out the drill-rope to suit the density of the soil through which the tools are drilling, said pitman is connected to an 85 adjustable pivot-plate 23 on said rocker, said plate being slotted and held at the desired adjustment, or with the contiguous end of the pitman at the desired distance from the axis of the rocker, by means of a set-screw. 90

The spudding-lever receives motion from a spudding-cam 24, which is of bifurcated construction, with an antifriction-roll 25 at its extremity to contact with the upper side of the lever, said cam being carried by a shaft 26, provided with an operating-pulley or sprocket-wheel 27, adapted to receive power from a suitable engine or operating mechanism. (Not illustrated.) The cam-shaft also carries a cone-pulley or sprocket-wheel 28, 100 which is connected by means of a chain or belt 29 with a similar reversed cone-pulley or

sprocket-wheel 30, arranged on the counter-shaft 31, said counter-shaft also carrying spaced reversely-disposed bevel-pinions 32 and 33.

5 Arranged in connection with the drill-rope is a tubular guide 34, mounted for rotary or rocking movement in registering upper and lower bearings 35 and 36, said guide being provided at diametrically opposite points with 10 longitudinal grooves 37 for the reception of parallel rods forming the sides of a slide 38, attached to the drill-rope and adapted to reciprocate in the grooves. Secured to the guide, between the planes of the journal-boxes 39 15 and 40, in which said upper and lower bearings are formed, is a pulley or sprocket wheel 41, traversed by a belt or chain 42, which extends around a pulley or chain wheel 43 on the upper extremity of an upright rock-shaft 44, said 20 rock-shaft carrying a bevel-gear 45, with which meshes a pinion 46 on the contiguous extremity of a reversible shaft 47, said reversible shaft carrying a gear 48, adapted to mesh with either of the bevel-pinions of said counter-shaft, and being disposed between the 25 planes thereof.

The slide, which is carried by the drill-rope to fit in the guide, is provided with terminal clamps 49, adapted to engage and hold the 30 drill-rope in contact with upper and lower curved seats 50, formed in the ends of the slide-frame, said clamp-plates being provided at opposite ends, respectively, with closed and open-sided perforations 51 and 52, engaged 35 by bolts 53, to facilitate the changing of the adjustment of the slide upon the drill-rope as the latter is fed through the guide. The slide is preferably made of such a length as to allow the drill-rope to be paid out a distance of 40 two or three feet or more for each adjustment.

The mechanism as above described is designed to impart to the drill-rope guide an oscillatory movement, or a rotary movement alternately in opposite directions, in order, 45 through the medium of the slide, to impart a similar movement to the drill-rope, and hence the drill-tools, in order to insure the drilling of a straight hole, and, in order to accomplish this alternately opposite rotary movement of 50 the rope-guide, it is necessary to reverse the rotation of the reversible shaft which receives motion from the counter-shaft 31. In the construction illustrated this reversal of the movement of said reversible shaft is accomplished by means of a slide 54, mounted for 55 movement transverse to the axis of said shaft in a slide-box 55, supported by the main frame. Connected to this slide is a lever 56, preferably of the bell-crank type, as shown, 60 and this bell-crank lever receives motion from an operating-lever 57 of the first order fulcrumed upon the slide-box. Operating in connection with the above mechanism is a crank-wheel 58, carried by a shaft 59, which 65 is connected with the main or operating shaft 26 by means of a worm 60 and a worm-gear 61. Said crank-wheel carries a wrist-pin 62,

operating in a slot 63 in the pitman 64, which is connected to the short arm of the operating-lever 57, said wrist-pin being adapted to 70 contact with opposite ends of the slot at intervals and thereby reverse the position of the operating-lever 57, and hence, through the bell-crank lever, of the slide. This slide is provided with a bearing in which is mounted 75 the contiguous end of the reversible shaft, and in one position of the slide the gear carried by the adjacent end of the reversible shaft is in mesh with one of the pinions on the counter-shaft, and when said slide is in 80 the other position said gear is in mesh with the twin pinion on the counter-shaft. Hence when the slide is in one position the reversible shaft receives rotary motion from the counter-shaft in one direction, while the opposite adjustment of the slide causes rotary motion of said reversible shaft in the opposite direction.

In order to insure the maintenance by the slide of either of its adjusted positions during the time that the wrist-pin of the crank-wheel is traversing the length of the slot in the pitman, I employ a locking device 65, having a pin or bolt 66 arranged in an opening in the upper side of the slide-box and adapted 95 to engage either of a pair of spaced sockets 67 and 68 in the slide, according to the position of the latter, and also having a trip-rod 69, which is arranged in the path of a pivotal trip-arm 70, disposed contiguous to the plane 100 of the crank-wheel. The free end of this trip-arm is disposed in the path of diametrically opposite trip-pins on the crank-wheel, and as the latter rotates said pins are brought successively into contact with the trip to 105 actuate the trip-rod and thus withdraw the locking pin or stud from engagement with the socket in which it has been seated.

From the foregoing description it will be seen that during the spudding operation the 110 rope-guide is turned alternately in opposite directions during a given number of revolutions depending upon the portions of the concave pulleys or sprocket-wheels traversed by the belt or chain 29, this oscillatory movement of 115 the drill-rope not interfering with the reciprocation thereof through the guide produced by the spudding mechanism.

In order to facilitate the mounting and dismounting of the rope-guide, the journal-blocks 39 and 40 are provided with bails 73, upon which are mounted cam-locks 74, said bails being provided at the extremities of their arms with hooks 75 to engage transverse pins or bolts 76, which intersect kerfs 77 in 120 the journal-blocks. Furthermore, the outer sides of the bearings in said journal-blocks are cut away, as shown at 78, to admit the drill-rope and allow the bearings to be arranged in alinement with the extremities of 125 the guide. Furthermore, in order to allow the feed-shaft 11 to be disconnected from the feed mechanism during the manual adjustment of the drill-rope, I mount the worm-gear 130

15 to slide upon the feed-shaft, and employ in connection therewith a bifurcated shifting-block 79, to which is connected an operating rod or stem 80, which is fitted to slide in guides 81 on the supporting-frame. By means of this rod or stem the gear may be moved out of engagement with the worm 16 to a position contiguous to the adjacent upright of the frame.

10 Various changes in the form, proportion, and the minor details of construction may be resorted to without departing from the spirit or sacrificing any of the advantages of this invention.

15 Having described my invention, what I claim is—

1. In a well-drilling apparatus, the combination of a rotatable drill-rope guide, a slide provided with means for attachment to a drill-rope, and mounted for reciprocatory and held from independent rotary movement in said guide, and means for communicating positive oscillatory movement, or rotary movement alternately in opposite directions, to the 25 guide, said means including a rock-shaft permanently connected by gearing with the guide, oppositely-rotated continuously-operating gears, and means for communicating motion from said gears, alternately, to the 30 rock-shaft, substantially as specified.

2. In a well-drilling apparatus, the combination of a rotatable guide, a slide provided with means for attachment to a drill-rope, and mounted for reciprocatory and held from 35 independent rotary movement in said guide, and means for communicating oscillatory movement, or rotary movement alternately in opposite directions, to said guide, said means including a rock-shaft and operating 40 devices, and a chain traversing and permanently connecting chain-wheels carried respectively by the guide and rock-shaft, substantially as specified.

3. In a well-drilling apparatus, the combination of a tubular rotatable guide having alined trunnions and an intermediate gear, spaced bearing-blocks of which one is removable, means for securing the removable bearing-block in operative relation with the other, 50 a slide provided with means for attachment to the drill-rope and mounted for reciprocatory and held from independent rotary movement in said guide, a rock-shaft and means for actuating the same, and operating connections between the rock-shaft and the gear of the guide, substantially as specified.

4. In a well-drilling apparatus, the combination with a rotatable guide and means for communicating motion thereto, of a slide having 60 parallel sides adapted to fit in opposite grooves of the guide, and also having its ends provided with alined rope-seats, terminal pivotal clamps mounted upon the ends of the slide to close said rope-seats, and means for 65 securing the clamps in operative relation with the rope-seats, the slides being adapted

to be introduced longitudinally into the guide, substantially as specified.

5. In a well-drilling apparatus, the combination of a rotary rope-guide through which 70 a drill-rope is adapted to extend, means for attachment to the drill-rope and fitted in said guide to allow reciprocatory and prevent independent rotary movement of said rope, upper and lower bearing-blocks in which the 75 extremities of said guide are fitted, swinging bails connected to the journal-blocks, cams mounted upon the bails for engagement with a derrick-post to secure the bearing-blocks in their operative positions, and means for communicating rotary movement to the rope-guide, substantially as specified.

6. In a well-drilling apparatus, the combination with a rotary rope-guide through which 80 a drill-rope is adapted to extend, and connections between said guide and a drill-rope whereby the latter is allowed reciprocatory and held from independent rotary movement, and means for communicating rotary movement alternately in opposite directions to the 85 rope-guide, said means including a reversible shaft, connections between said shaft and the rope-guide, a counter-shaft having oppositely-disposed pinions adapted to alternately engage a gear on said reversible shaft, and operating devices for the counter-shaft, substantially as specified.

7. In a well-drilling apparatus, the combination with a rotary rope-guide through which 90 a drill-rope is adapted to extend, and connections between the rope-guide and the drill-rope whereby the latter is allowed reciprocatory and held from independent rotary movement, a reversible shaft operatively connected with the rope-guide, a slide having one end 95 of the reversible shaft mounted therein and arranged for movement in a direction transverse to said shaft, a counter-shaft carrying the twin oppositely-disposed pinions for alternate engagement by a gear on the transversely-movable extremity of the reversible shaft, and means for communicating continuous rotary movement in a uniform direction to the counter-shaft, substantially as specified.

8. In a well-drilling apparatus, the combination with a rotary rope-guide, and connections between the rope-guide and the drill-rope whereby the latter is allowed reciprocatory and held from independent rotary movement, a reversible shaft operatively connected 100 with said rope-guide, a counter-shaft having twin oppositely-disposed pinions for alternate engagement with a gear on the contiguous extremity of said reversible shaft, a slide adapted 105 for reciprocatory movement to cause the alternate engagement of said pinions with the gear on the reversible shaft, a crank-wheel having a wrist-pin, an operating-lever connected with said slide, a pitman having a 110 slot in which the wrist-pin of said crank-wheel operates, to alternately shift the operating-

lever, and means for communicating continuous rotary motion to the crank-wheel and counter-shaft, substantially as specified.

9. In a well-drilling apparatus, the combination with a rotary rope-guide, and connections between the rope-guide and the drill-rope whereby the latter is allowed reciprocatory and held from independent rotary movement, a reversible shaft operatively connected with said rope-guide, a counter-shaft having twin oppositely-disposed pinions for alternate engagement with a gear on the contiguous extremity of said reversible shaft, a slide adapted for reciprocatory movement to cause the alternate engagement of the said pinions with the gear on the reversible shaft, a crank-wheel operatively connected with the slide to shift the latter at intervals from one limit of its movement to the other, a locking device including a pin or stud adapted to engage and hold the slide in its operative positions, trip mechanism operatively connected with said crank-wheel for releasing the slide at intervals, and means for communicating rotary movement to the crank-wheel and counter-shaft, substantially as specified.

10. In a well-drilling apparatus, the combination with a rotary rope-guide, and connections between the rope-guide and the drill-rope whereby the latter is allowed reciprocatory and held from independent rotary movement, a reversible shaft operatively connected with said rope-guide, a counter-shaft having twin oppositely-disposed pinions for alternate engagement with a gear on the contiguous extremity of said reversible shaft, a slide adapted for reciprocatory movement to cause the alternate engagement of said pinions with the gear on the reversible shaft, a crank-wheel, connections between the crank-wheel and the slide for shifting the latter at intervals to opposite limits of its movement, a locking device having a pin or stud to engage the slide at the limits of its movement, a trip-rod connected to the pin or stud, a trip-arm ar-

ranged in the path of the trip-pin on said crank-wheel, the extremity of the trip-rod being arranged in the path of said trip, and means for communicating rotary motion to the counter-shaft and crank-wheel, substantially as specified.

11. In a well-drilling apparatus, the combination with a rotary rope-guide of tubular construction, a drill-rope extending through said guide, and a slide attached to the drill-rope and mounted for reciprocation in the guide, a spudding-lever carrying a spudding-pulley traversed by said drill-rope, a reversible shaft operatively connected with said rope-guide, a driving-shaft carrying a cam for engagement with the spudding-lever, a counter-shaft having twin oppositely-disposed pinions for alternately engaging and communicating rotary movement in opposite directions to a gear on said reversible shaft, cone-pulleys arranged respectively on the counter and main shafts and traversed by a belt, and means connected with the main shaft for causing the alternate engagement of said pinions with the gear on the reversible shaft, substantially as specified.

12. In a well-drilling apparatus, the combination with a spudding-lever, a drum for a drill-rope, a feed-shaft operatively connected with the drum, a worm meshing with a worm-gear on the feed-shaft, a ratchet-wheel fixed to the spindle of the worm, a pawl for engagement with the ratchet-wheel, a slotted pivot-plate carried by the spudding-lever contiguous to its fulcrum, a set-screw for securing said plate at the desired adjustment, and a pitman connecting the plate with the pawl, substantially as specified.

In testimony that I claim the foregoing as my own I have hereto affixed my signature in the presence of two witnesses.

PRESSLEY P. MARSII.
